C. PHILLIPS, JR

BINDING POST

Filed March 31, 1922

FIG. 1.

FIG. 2.

FIG. 3.

FIG. 4. Charles Phillips, Jr.
INVENTOR

BY Victor J. Evans

ATTORNEY

John D. Baker Jr.
WITNESS

UNITED STATES PATENT OFFICE.

CHARLES PHILLIPS, JR., OF PHILADELPHIA, PENNSYLVANIA.

BINDING POST.

Application filed March 31, 1922. Serial No. 548,408.

To all whom it may concern:

Be it known that I, CHARLES PHILLIPS, Jr., a citizen of the United States, residing at Philadelphia, in the county of Philadelphia and State of Pennsylvania, have invented new and useful Improvements in Binding Posts, of which the following is a specification.

This invention relates to binding posts such as are employed in the electrical arts and industries for connecting up the terminals of an energized circuit and it has for its primary object to provide a binding post characterized by a novel means for locking the terminal wire thereto.

Another object of this invention is to provide a binding post having a terminal wire locking means which will not cut or injure said wire, while ensuring its secure retention in place.

A further object of this invention is to provide a binding post which may be used for temporarily connecting up a terminal wire for experimental or other analogous purpose; or, alternatively locking a terminal wire thereto.

With the foregoing and other objects in view as will be more apparent from the following description my invention consists essentially in providing a binding post with a transverse bore at right angles to the wire receiving opening and in slidably mounting in said transverse bore a pin having a cut-away wedge-like portion for impingement on the terminal wire, and in means for locking said pin against axial movement.

In the further disclosure of the invention reference is to be had to the accompanying sheet of explanatory drawings constituting a part of this specification, and in which like characters of reference designate the same or corresponding parts in all the views.

Figure 1 is an elevation of one embodiment of my novel form of binding post.

Figure 2 is a similar elevational view but taken at right angles to the preceding figure.

Figure 3 is a central vertical section taken through a slightly modified form of the binding post; and,

Figure 4 is a top plan view of the same.

Referring more particularly to the views a base or the like of appropriate material is characterized by the numeral 5 and to which my novel binding post is to be at-

tached. The said binding post comprises a cylindric or other appropriately cross sectioned body 6, the lower end whereof is axially bored at 7 to receive an attaching screw or the like 8 by means of which the post is securely held to or mounted on the base 5. In Figures 1 and 2 I have indicated the body 6 as circular in cross-section, while in Figures 3 and 4 the same is of rectangular cross-section; but it will be obvious that any other appropriately cross sectioned body may be employed.

The ordinary terminal wire receiving opening is designated by the numeral 9 and it will be observed and noted that said opening is diametrically disposed relative to the vertical axis of the body 6. At right angles to the aforesaid opening 9 I drill or otherwise form a transverse bore 10 and on an examination of Figures 2 and 3 it will be clearly seen that this bore 10 is positioned to traverse through or cut into the wire receiving opening 9. Slidably fitting the transverse bore 10 is a pin 11, the wall whereof is cut out wedge-fashion as shown at 12 to a sufficient extent so that when the deepest portion 13 thereof is over the terminal wire 14, the latter may be freely passed into and out of—or through—the opening 9. Now it will be perfectly clear that the 85 slideable pin 11 is first inserted in the transverse bore 10 before the terminal wire is passed through the opening 9, and on an examination of Figure 2 it will be apparent that when the said pin is moved to the left hand the deepest part 13 of the cut out or wedge-like recession 12 can be positioned over the terminal wire 14 and thereby permit of its easy movement relative to the binding post or body 6. On the other hand, the 90 forcing of the pin 11 towards the right hand in the same figure will result in the jamming of the wedge-like cut-out 12 on to the terminal wire 14 and its frictional retention in place relative to the binding post or body 6. 100

In order to provide an effective and simple means for locking the pin 11 and terminal wire 14 firmly together I preferably screw thread the outer ends of said pin 11 to receive lock nuts 15, 15' the bores whereof are slightly countersunk at 16 so that when a nut 15 or 15' is screwed home tight against the post or body 6 the outer end of the pin 11 may be hammered or expanded thereinto as shown at 17. This feature of the invention 110

I deem of considerable importance where the post is subject to heavy vibration—as on automobiles for instance—as an examination of Figure 3 more particularly will conclusively show that when the nut 15' for example, is jammed and locked—as shown—the terminal wire 14 will be immovably secured in the post or body 6.

From the foregoing it will be quite clear to those acquainted with the art that by my invention I have provided an extremely simple and efficient binding post, the numerous advantages and usages whereof will be self-evident without further explanation or description.

While there has been shown and described the best form of my invention at present known to me, it will be apparent the same is susceptible of minor detail changes in shape and disposition of the several parts, and the right is hereby reserved to make

such changes and variations as fairly lie within the scope of the appended claim.

Having described my invention, what I claim as new and desire to secure by Letters Patent is:

As a new article of manufacture a terminal wire holding and locking member for binding posts comprising a slidable pin for passage through a bore at right angles to and intersecting a wire receiving opening through the binding post, said slidable pin having an inclined notched-out part in the wall thereof for frictional engagement upon a terminal wire when connected into the binding post, and nuts threaded on the outer ends of the aforesaid pin whereby the same may be locked immovably in the binding post.

In testimony whereof I affix my signature.

CHARLES PHILLIPS, JR.
